F. CARNAHAN,
CONTROL DEVICE FOR PNEUMATICS,
APPLICATION FILED DEC. 21, 1916.

1,289,391.

Patented Dec. 31, 1918.

UNITED STATES PATENT OFFICE.

FRANK CARNAHAN, OF SOUTH BOSTON, MASSACHUSETTS, ASSIGNOR TO EMERSON PIANO COMPANY, OF BOSTON, MASSACHUSETTS, A CORPORATION OF ILLINOIS.

CONTROL DEVICE FOR PNEUMATICS.

1,289,391.

Specification of Letters Patent. Patented Dec. 31, 1918.

Application filed December 21, 1916. Serial No. 188,144.

To all whom it may concern:

Be it known that I, FRANK CARNAHAN, a citizen of the United States, residing at South Boston, in the county of Suffolk and 5 State of Massachusetts, have invented certain new and useful Improvements in Control Devices for Pneumatics; and I do hereby declare the following to be a full, clear, and exact description of the invention, such 10 as will enable others skilled in the art to which it appertains to make and use the same.

My invention consists in the novel features hereinafter described, reference being 15 had to the accompanying drawing which illustrates one embodiment of the invention selected by me for purposes of illustration together with a modified form of the invention, and the said invention is fully disclosed 20 in the following description and claims.

In the operation of pneumatics for effecting the operation of various parts of a piano, in a pneumatic piano player, difficulty is experienced in securing an instantaneous actuation of pneumatics of relatively large capacity, such as are employed for the purpose of producing, for example, the loud and soft effects by the operation of the hammer rail or rails or the dampers usually controlled by the loud and soft pedals when the instrument is played by hand. Such actuating pneumatics are ordinarily connected at the time of use with the suction apparatus by means of secondary pneumatic devices controlling primary valve mechanisms which require an appreciable time for their operation, and normally control such small openings or passages that the exhaustion of air from the actuating pneumatic or pneumatics is not as quickly and sharply responsive as is desirable, and as can be readily obtained by the actuation of ordinary loud and soft pedals when the instrument is played by hand.

45 The object of my invention is to provide a novel control device, which may be operated manually or automatically from the tracker board, and which will instantaneously place in communication with the suction apparatus of the player a relatively large passage communicating with the pneumatic to be actuated so as to secure an instantaneous actuation of the latter, while at the same time preventing the possibility

of whistling or other noises, which frequently result from the passage of a relatively large body of air through relatively small apertures.

Obviously the specific details of my invention may be varied to suit the particular use 60 to which it is applied, and the particular pneumatics which it is to control. For the purpose of illustrating the invention, I have selected the embodiments shown herein, and in Figures 1, 2 and 3 I have shown an embodiment of the invention which may be conveniently employed for the purpose of controlling pneumatics operatively connected with the hammer rail or rails for the production of soft effects under manual control. 70 It is customary to form the hammer rail in two parts, one of which is supported in rear of the bass hammers, and the other of which is supported in rear of the treble hammers, so that either section of the 75 hammer rail can be operated separately, or both portions may be operated simultaneously as desired. In this instance, therefore, I have shown a duplex embodiment of my invention for the purpose of independently 80 or simultaneously actuating the sections of the hammer rail.

Referring to the drawing:

Fig. 1 is a view partly in section of my improved control device for pneumatics 85 showing it applied to the control of the pneumatics for operating the hammer rail or rails of a piano in connection with a pneumatic player action.

Fig. 2 is a section on line 2—2 of Fig. 1. 90

Fig. 3 is a section on line 3—3 of Fig. 1.

Fig. 4 represents a modification of my improved control device shown, in this instance, as arranged for lifting the dampers to produce loud effects and controllable 95 either manually through suitable push buttons or through the tracker board.

In this form of my invention 1 represents a valve casing provided with a suction chamber, 2, adapted to be connected with the suction devices of the player, in this instance, by means of a relatively large pipe or passage, 3, leading to the wind chest (not shown) which may be of ordinary construction, and provided with the usual feeders or pumping bellows operated by foot pedals or by a suitable motor. The valve casing, 100 is also provided on each side of the suction

chamber with a valve chamber, 4, which is preferably open to the atmosphere at the top, and is provided with a normally open valve, 5, in this instance, a hinged valve, 5, which is provided with means normally tending to close it. In this instance, I have shown the valve, 5, provided with a weight, 6, for this purpose. Each of the valve chambers, 4, communicates with the suction chamber by means of a passage, 7, of substantially the same cross sectional area as the suction pipe or passage, 3, which passages 7 are normally closed by means of vertically movable sliding valves, 8-8, and in order to obviate the necessity of too great a travel for said slide valves, I prefer, to make the apertures or passages, 7, oblong, with their greatest diameters perpendicular to the direction of travel of the valves, 8, as shown in Figs. 2 and 3. Each of the valves is flexibly secured to an actuating valve stem 9, in this instance, by means of a screw, 10, loosely engaging an aperture in the valve stem, which is flattened in that portion through which the screw passes, and I provide an operative connection between each valve 8 and its corresponding valve, 5, in which there is a provision for lost motion to the end that the valve, 5, shall be permitted to close before the valve, 8, opens the passage, 7, and by which the valve, 5, is positively opened after the valve, 8, is closed. Various means can be employed for this purpose, but I have shown a very simple means which consists in providing the valve stem, 9, with an extension, 11, projecting upwardly into position to engage the valve, 5, at the instant that the valve, 8, closes the aperture, 7, so as to lift the valve, 5, and place the valve chamber 4, in communication with the atmosphere. It follows from this construction that on the downward movement of the valve, 8, the valve, 5, will be permitted to close before the valve, 8, opens the passage, 7, as will be readily understood.

Each of the valve chambers, 4, communicates by a relatively large air passage, with the pneumatic controlled by its valves, and, in this instance, I have shown each valve chamber provided with a pipe, 12, which is connected by a tube, 13, with a pneumatic, 14. One of the pneumatics, 14, is provided with a rod, 15, operatively connected with one section of the hammer rail, as for example, the base section, and the other pneumatic, 14, is connected by a rod, 15^a, with the other section of the hammer rail, as the treble section. When the valve, 5, is open the pneumatic connected with the corresponding valve chamber will be in expanded condition as it will be placed in connection with the atmosphere, while the valve, 8, closes the aperture, 7, communicating with the suction. The loose connection permits

the valve, 8, to seat accurately and said valve will be firmly held in closed position by the suction.

Various means may be provided for actuating the valves, 8 and 5, either manually or otherwise. In the present instance, in Fig. 1, I have shown the valve mechanism supported in a recess, 16, in the underside of the key rail or front rail of the piano, in which it is held, for example, by means of the screws, 17, but obviously it may be located at any other convenient part of the structure, and the manual or other devices for actuating it may be connected to the valve stems, 9, in any desired manner. Where, as shown in Fig. 1, it is supported in the key rail, the valve stems, 9, may be conveniently actuated by means of push buttons on the upper surface of the rail as indicated at 18 and 19, said push buttons being connected with rods, 20, passing through the key rail and connected at their lower ends to the respective valve stems, 9, each of the rods, 20, being provided with a retracting spring, 21, engaging a nut or collar, 22, on the rod, 20, for example, as shown in Figs. 1 and 2.

It will be seen that a passage of relatively large cross sectional area is provided from each of the pneumatics, 14, to the suction mechanism of the player through the pipes, 13, passages, 7, and suction pipe, 3, the valves, 8, being located across said passages and the valves, 5, controlling the communication with the atmosphere located in each instance between the valve, 8, and the pneumatic, 14.

In the operation of a piano player equipped with such a control device, if it be supposed that the operator desires to soften the action of the treble hammers, he will depress the button, 19, manually, as indicated in Fig. 1, thereby depressing the valve stem, 9. The first effect of this is to permit the valve, 5, for the corresponding valve chamber to close and shut off the communication with the atmosphere. The further movement of the valve stem, 9, opens the valve, 8, and instantly places the pneumatic in communication with suction through a passage of relatively large cross sectional area, thereby causing the instantaneous collapse of the pneumatic and the instantaneous operation of the part connected therewith, in this instance, the treble hammer rail. In the same manner, the bass hammer rail can be actuated by depressing the button, 18, and obviously both hammer rails can be instantaneously and simultaneously actuated by simultaneously depressing both buttons, 18 and 19.

As soon as either of the buttons is released, the valve stem, 9, is raised by the spring, 21, connected therewith, thereby first closing the passage, 7, by means of the

valve, 8, and then instantly opening the valve, 5, placing the corresponding pneumatic in communication with the atmosphere so that it may be instantly filled with air and open, thus restoring its connected section of the hammer rail or other part to which it may be connected to its normal position.

Obviously if only one pneumatic is to be operated only one of the valve chambers, 4, and the associated parts is required, and my improved control device may be actuated directly by hand, or indirectly by means of a pneumatic, which may be controlled either manually or from the tracker board, and in Fig. 4, I have shown a modified form of my invention, in this instance, arranged to operate a single pneumatic as the pneumatic for lifting the dampers to produce loud effects, the control device being arranged to be operated either by a push button, as in the form shown in Figs. 1, 2 and 3, or by a special pneumatic which may be actuated either by hand or from the tracker board.

In this figure, 1^a, represents the valve casing, which is provided with a suction chamber, 2^a, connected to the suction apparatus of the piano, as by a pipe, 3^a, and said valve casing is also provided with a valve chamber, 4^a, communicating by a passage, 7^a, with the suction chamber and normally open to the atmosphere at its upper end, the said open end being provided with the valve, 5^a, in this instance, provided with the weight, 6^a, to assist in closing the same. The passage, 7^a, is controlled by the slide valve, 8^a, flexibly mounted on the valve stem, 9^a, to which it is secured by the screw, 10^a, the upper end, 11^a, of the valve stem extending into position to raise the valve, 5^a, when the valve, 8^a, is closed, and to permit the valve, 5^a, to close before the valve, 8^a, is opened.

The valve chamber, 4^a, is connected by means of a pipe, 12^a, and tube, 13^a, with a large pneumatic, 25, connected by a rod, 26, in this instance, to the dampers for elevating the same when the pneumatic has collapsed. The valve stem, 9^a, is operatively connected with a push button, 18^a, by means of a rod, 20^a, provided with a nut, 22^a, and retracting spring, 21^a, as in the form hereinbefore described, which normally holds the button in retracted position, and the valve stem, 9^a, in position to close the valve, 8^a, and open the valve, 5^a.

The foregoing portions of the apparatus, shown in Fig. 4, are substantially identical with the corresponding parts, shown in Figs. 1, 2 and 3. In this instance, I have shown a small pneumatic, 30, provided with an arm, 31, for engaging a nut or collar, 32, on the valve stem, 9^a, the movable member of the pneumatic, indicated at 30^a, to which the arm, 31, is connected, being provided

with a retracting spring, 33, of greater strength than the retracting spring, 21^a. The pneumatic, 30, is connected with the suction apparatus, in any desired way, for example, by means of a small pipe, 34, leading to the suction chamber, 2^a, or to any other part in communication with the wind chest and feeders. Where it is desired to control the pneumatic, 30, manually a suitable manually operated valve will be provided for admitting air from the atmosphere to the pneumatic, 30. In this instance, I have shown such a valve at 40, in connection with a small valve casing, 41, connected by pipes, 42 and 43, with the pneumatic, 30, the valve, 40, being normally held closed by a spring, 44, and provided with an actuating button, 45. The connection between the pneumatic, 30, and suction will normally cause the collapse of the pneumatic, 30, and will overcome the spring, 33. By depressing the button, 45, the valve, 40, will be opened placing the pneumatic, 30, in communication with the atmosphere, thus permitting the pneumatic, 30, to expand under the action of its spring, 33, which will actuate the valve stem, 9^a, overcoming the weaker spring, 21^a, to close the valve, 5^a, and open the valve, 8^a, in the manner hereinbefore described. The air inlet pipe, 43, leading to the pneumatic, 30, may also be placed in connection with a special aperture, 50, in the tracker board, indicated at 51, by means of a pipe, 52, for example, the aperture, 50, being normally closed by the paper roll. When it is desired to operate the pneumatic, 25, a suitable aperture in the paper roll indicated at 53, in dotted lines, passing over the aperture, 50, will admit air to the small pneumatic, 30, and permit the actuation of the valves, 5^a and 8^a, by the spring, 33, in the manner hereinbefore described. Obviously either one or the other of the manual controls or the tracker control, shown in Fig. 4, could be omitted, if desired.

In the operation of my improved control device, the depression of the valve stem instantaneously places the pneumatic controlled thereby in communication with the suction apparatus by means of a large and ample passage so that as before stated the action of the pneumatic is rendered instantaneously responsive and by reason of this large passage the movement of the air therethrough is silent, and whistling and other noises are entirely obviated.

While I have shown my invention applied to pneumatics for controlling the hammer rail or rails, and for raising the dampers, it can be applied, as will be evident, to pneumatics designed for any other purpose, and may be constructed singly or in multiple and operated manually or automatically, or manually and automatically as desired and as fully set forth herein. I do not limit my

self to the exact details of construction herein shown and described as variations may be made therein without departing from the spirit of my invention.

5. What I claim and desire to secure by Letters Patent is:

1. In a pneumatic piano player, the combination with a power pneumatic, and an air connection extending from said pneumatic to the suction means for the player, a valve casing located in said connection and provided with a control valve aperture of unequal diameters, and with a vent aperture communicating with the atmosphere, a controlling slide valve normally engaging said controlling valve aperture and closing the same, a manually operated valve stem for said control valve, a vent valve for closing the vent aperture, yielding means normally tending to move the vent valve toward the vent aperture, a part connected with the valve stem for engaging the vent valve and holding it in open position when the control valve is closed, and a spring operatively connected with the valve stem for normally holding the control valve closed and the vent valve open, said control valve aperture having its greatest diameter disposed perpendicularly to the direction of travel of the controlling slide valve.

2. In a pneumatic piano player, the combination with a power pneumatic, and an air connection extending therefrom to the suction means for the player, of a valve casing in said connection provided with a control valve aperture having unequal diameters, and provided with a vent aperture, a controlling slide valve normally closing said control aperture, a manually operable valve stem flexibly connected with said slide valve to permit the slide valve to remain tightly closed, when in closed position, by suction, a spring operatively connected with said valve stem for holding the slide valve normally in closed position, a vent valve for closing said vent aperture, said valve stem having a part connected therewith for normally holding the vent valve in open position, and yielding means normally tending to move the vent valve toward the vent aperture, said valve control aperture having its greatest diameter perpendicular to the direction of movement of the controlling slide valve.

5. The combination with a power pneumatic, suction means for exhausting air therefrom, and an air connection of relatively large capacity connecting said pneumatic and suction means, of a valve casing in said connection provided with a valve control aperture of substantially the same cross sectional area as the said air connection, a controlling slide valve normally closing said aperture, said valve casing being provided with a vent aperture, a normally open vent

valve for closing said vent aperture, a manually operable device connected with the controlling valve and having a part engaging the vent valve and holding it open, and yielding means connected with said device for maintaining the controlling valve closed and the vent valve open.

4. The combination with a power pneumatic, suction means for exhausting air therefrom, and an air connection of relatively large capacity connecting said pneumatic and suction means, of a valve casing in said connection provided with a valve control aperture of substantially the same cross sectional area as the said air connection, a controlling slide valve normally closing said aperture, said valve casing being provided with a vent aperture, a normally open vent valve for closing said vent aperture, a valve stem connected with said controlling valve and having a part engaging the vent valve for holding the latter open when the controlling valve is closed, a spring operatively connected with the valve stem for moving it in a direction to close the controlling valve and open the vent valve, and a manually operable device connected with said valve stem for moving it in the direction to open the controlling valve and permit the vent valve to close.

5. The combination with a pneumatic, suction means for exhausting the air therefrom, and an air connection between said pneumatic and suction means, of a normally closed sliding control valve for opening and closing said connection, said connection being provided with a vent aperture between said control valve and said pneumatic communicating with the atmosphere, a normally open vent valve for closing said aperture, means normally tending to close the vent valve, a longitudinally movable actuating stem for the control valve having a part for engaging the vent valve and opening it after the control valve is completely closed, said part being capable of movement away from its operative position with respect to the vent valve before the control valve is opened, to permit the vent valve to close, yielding means for holding the control valve normally in closed position; and means including a manually operated device connected with the valve stem for moving it in the direction to open the control valve.

6. The combination with a pneumatic, suction means for exhausting the air therefrom and an air connection between said pneumatic and suction means, of a normally closed sliding control valve for opening and closing said connection, said connection being provided with a vent aperture between said control valve and said pneumatic, communicating with the atmosphere, a normally open gravity vent valve adapted to be closed by gravity, a vertically disposed actuating

- stem connected with said control valve and having a part extending into position to engage the vent valve after the control valve is closed to open the vent valve and hold it open, said part being capable of movement away from the vent valve after it is closed and before the control valve is opened, yielding means connected with said stem normally holding it in position to close the control valve and open the vent valve, and means including a manually operated device for moving said stem in the opposite direction to permit the vent valve to close and thereafter open the control valve.
- 15 7. The combination with a pneumatic, suction means for exhausting the air therefrom, and an air connection of relatively large cross sectional area between said pneumatic and suction means, of a normally closed controlling valve for said connection, said connection being provided with a vent aperture between said control valve and the pneumatic, a normally open vent valve for closing said vent aperture, a valve stem for said control valve provided with a part normally engaging the vent valve and holding it open, a spring operatively connected with said valve stem for holding the control valve closed and the vent valve open, a pneumatic actuating device operatively connected with said valve stem, an air connection of relatively small cross sectional area extending from said pneumatic actuating device to said suction means, and manually operated means for establishing communication between said pneumatic actuating device and the atmosphere.
8. The combination with a pneumatic, suction means for exhausting the air therefrom, and an air connection of relatively large cross sectional area between said pneumatic and suction means, of a normally closed controlling valve for said connection, said connection being provided with a vent aperture between said control valve and the pneumatic, a normally open vent valve for closing said vent aperture, a valve stem for said control valve provided with a part normally engaging the vent valve and holding it open, a spring operatively connected with said valve stem for holding the control valve closed and the vent valve open, a pneumatic actuating device operatively connected with said valve stem, an air connection of relatively small cross sectional area extending from said pneumatic actuating device to said suction means, a tracker board, an air connection from said pneumatic actuating device to an aperture in the tracker board, and an independent manually operable device for effecting the actuation of said valves independently of the tracker board.
9. The combination with a pneumatic, suction means for exhausting the air therefrom, and an air connection of relatively large cross sectional area between said pneumatic and suction means, of a normally closed controlling valve for said connection, said connection being provided with a vent aperture between said control valve and the pneumatic, a normally open vent valve for closing said vent aperture, a valve stem for said control valve provided with a part normally engaging the vent valve and holding it open, a spring operatively connected with said valve stem for holding the control valve closed and the vent valve open, a pneumatic actuating device operatively connected with said valve stem, an air connection of relatively small cross sectional area extending from said pneumatic actuating device to said suction means, a tracker board, an air connection from said pneumatic actuating device to an aperture in the tracker board, and an independent manually operable device for effecting the actuation of said valves independently of the tracker board.
- 10 11. The combination with a pneumatic, suction means for exhausting the air therefrom, and an air connection of relatively large cross sectional area between said pneumatic and suction means, of a normally closed controlling valve for said connection, said connection being provided with a vent aperture between said control valve and the pneumatic, a normally open vent valve for closing said vent aperture, a valve stem for said control valve provided with a part normally engaging the vent valve and holding it open, a spring operatively connected with said valve stem for holding the control valve closed and the vent valve open, a pneumatic actuating device operatively connected with said valve stem, an air connection of relatively small cross sectional area extending from said pneumatic actuating device to said suction means, and an independent manually operable valve for actuating said pneumatic actuating device independently of the tracker board.
- 15 12. The combination with a pneumatic, suction means for exhausting the air therefrom, and an air connection between said pneumatic and suction means, of a normally closed control valve for said connection, said connection being provided with a vent aperture between said control valve and said pneumatic, communicating with the atmosphere, a normally open vent valve for closing said vent aperture, a pneumatic actuating device for both of said valves, connections between said pneumatic actuating device and said valves including means for effecting the closing of the vent valve before the opening of the control valve, and the opening of the vent valve after the closing of the control valve, an air connection between said pneumatic actuating device and said suction means, a tracker board and an air connection from said pneumatic valve actuating device to an aperture in the tracker board, and an independent manually operable device for actuating said valves independently of the tracker board.
13. The combination with a pneumatic, suction means for exhausting the air therefrom, and an air connection between said pneumatic and suction means, of a normally closed control valve for said connection, said connection being provided with a vent aperture between said control valve and said pneumatic, communicating with the atmosphere, a normally open vent valve for closing said vent aperture, a pneumatic actuating device for both of said valves, connections between said pneumatic actuating device and said valves including means for effecting the closing of the vent valve before the opening of the control valve, and the opening of the vent valve after the closing of the control valve, an air connection between said pneumatic actuating device and said suction means, a tracker board, and an air connection from said pneumatic valve actuating device to an aperture in the tracker board.

- tracker board, a secondary air connection from said valve actuating pneumatic to the atmosphere, and a manually controlled normally closed valve for said secondary air connection.
12. The combination with a pneumatic, suction means for exhausting the air therefrom, and an air connection between said pneumatic and suction means, of a valve 10 casing forming part of said air connection, and provided with a port in communication with the suction means, and also provided with a vent aperture communicating with the atmosphere, a sliding valve in said 15 casing for normally closing said port, a normally open vent valve for closing said vent aperture, yielding means operative to close said vent valve, a valve stem connected with said sliding control valve and having a part 20 for engaging the vent valve to open it after the control valve is closed and to hold it normally in open position, yielding means connected with said valve stem to normally hold the control valve closed, and the vent 25 valve open, and means for moving said valve stem against the action of said yielding means to effect the closing of the vent valve and the opening of the control valve.
13. The combination with a pneumatic, suction means for exhausting the air therefrom, and an air connection between said pneumatic and suction means, of a valve 30 casing forming part of said air connection, and provided with a port in communication with the suction means, and also provided with a vent aperture communicating with the atmosphere, a sliding valve in said casing 35 for normally closing said port, a normally open vent valve for closing said vent aperture, yielding means operative to close said vent valve, a valve stem connected with said sliding control valve, and having a part 40 for engaging the vent valve to open it after the control valve is closed, and to hold it normally in open position, yielding means connected with said valve stem to normally hold the control valve closed, and the vent 45 valve open, a pneumatic device operatively connected with said valve stem for moving it against the action of said yielding means, an air connection from said pneumatic actuating device to said suction means, a tracker board, an air vent connection from 50 said actuating pneumatic to an aperture in the tracker board.
14. The combination with a pneumatic, suction means for exhausting the air therefrom, and an air connection between said 55 pneumatic and suction means, of a valve casing forming part of said air connection, and provided with a port in communication with the suction means and also provided with a vent aperture communicating with the atmosphere, and means for opening and closing said air vent connection.
15. The combination with a pneumatic, suction means for exhausting the air therefrom, and an air connection between said 60 pneumatic and suction means, of a valve casing forming part of said air connection, and provided with a port in communication with the suction means and also provided with a vent aperture communicating with the atmosphere, a sliding valve in said casing for 65 normally closing said port, a normally open vent valve for closing said vent aperture, yielding means operative to close said vent valve, a valve stem connected with said sliding control valve and having a part for engaging the vent valve to open it after the control valve is closed, and to hold it normally in open position, yielding means connected with said valve stem to normally hold the control valve closed, and the vent valve open, a pneumatic device operatively connected with said valve stem for moving it against the action of said yielding means, an air connection from said pneumatic actuating device to said suction means, a tracker board, an air vent connection from said actuating pneumatic to an aperture in the tracker board.
16. The combination with a pneumatic, suction means for exhausting the air therefrom, and an air connection between said 115 pneumatic and suction means, of a valve casing forming part of said air connection, and provided with a port in communication with the suction means, and also provided with a vent aperture communicating with the 120 atmosphere, a sliding valve in said casing for normally closing said port, a normally open vent valve for closing said vent aperture, yielding means operative to close said vent valve, a valve stem connected with said 125 sliding control valve and having a part for engaging the vent valve to open it after the control valve is closed, and to hold it normally in open position, yielding means connected with said valve stem to normally hold the control valve closed, and the vent valve open, a pneumatic device operatively connected with said valve stem for moving it against the action of said yielding means, an air connection from said pneumatic actuating device to said suction means, a tracker board, an air vent connection from said actuating pneumatic to an aperture in the tracker board.

the control valve closed, and the vent valve open, a pneumatic device operatively connected with said valve stem for moving it against the action of said yielding means, 5 an air connection from said pneumatic actuating device to said suction means, a tracker board, an air vent connection from said actuating pneumatic to an aperture in the tracker board, and a manually operated 10 device for effecting the operation of said valve stem independently of the tracker board.

17. The combination with a pneumatic, suction means for exhausting the air therefrom, and an air connection between said pneumatic and suction means, of a valve casing forming part of said air connection, and provided with a port in communication with the suction means, and also provided with a 20 vent aperture communicating with the atmosphere, a sliding valve in said casing for normally closing said port, a normally open vent valve for closing said vent aperture,

yielding means operative to close said vent valve, a valve stem connected with said sliding control valve and having a part for engaging the vent valve to open it after the control valve is closed, and to hold it normally in open position, yielding means connected with said valve stem to normally hold 25 the control valve closed, and the vent valve open, a pneumatic device operatively connected with said valve stem for moving it against the action of said yielding means, an air connection from said pneumatic actuating device to said suction means, a tracker board, an air vent connection from said actuating pneumatic to an aperture in the tracker board, a secondary air vent connection from the said actuating pneumatic, 40 a manually operated normally closed valve for said secondary air vent, and an independent manually operated device connected with the said valve stem.

In testimony whereof I affix my signature. 45
FRANK CARNAHAN.
